(57) **CLAIM**

The ornamental design for a solution dispenser, as shown and described.

DESCRIPTION

FIG. 1 is a perspective view of a solution dispenser showing the new design;

FIG. 2 is a side view thereof;

FIG. 3 is a front end view thereof;

FIG. 4 is a rear end view thereof;

FIG. 5 is a top plan view thereof; and,

FIG. 6 is a bottom plan view thereof.

The tubular container attached to the solution dispenser and illustrated in broken lines in FIG. 1 does not form a part of the invention.

The broken lines in FIGS. 1-6 illustrating the pad attached to the solution dispenser indicate the bounds of the claimed design and form no part thereof.
